(57) CLAIM

The ornamental design for an advertisement apparatus attached to the face of bezel, as shown and described.

DESCRIPTION

FIG. 1 is a perspective view of an advertisement apparatus attached to the face of bezel;

FIG. 2 is a front elevational view thereof;

FIG. 3 is a rear elevational view thereof;

FIG. 4 is a right-side elevational view thereof;

FIG. 5 is a left-side elevational view thereof;

FIG. 6 is a bottom plan view thereof;

FIG. 7 is a top plan view thereof;

FIG. 8 is an exploded perspective view thereof; and,

FIG. 9 is a rear exploded perspective view thereof.

The portions of the advertisement apparatus attached to the face of bezel and the monitor shown in broken lines form no part of the claimed design.
